Attorney

UNITED STATES PATENT OFFICE.

JOHN F. ALLEN, OF ERIE, PENNSYLVANIA, ASSIGNOR OF ONE-THIRD TO J. ALLISON HIMROD AND ONE-THIRD TO EDWARD E. ALLEN, BOTH OF ERIE, PENNSYLVANIA.

VULCANIZING MOLD.

Application filed January 17, 1925. Serial No. 3,167.

This invention is designed to improve vulcanizing molds, particularly such molds as are used for vulcanizing battery boxes. In the vulcanizing of such boxes a core is required which vulcanizes the interior of the box. Difficulty has been experienced in forming the core sections, where there are a plurality of them as is common with battery boxes, so as to retain their shape under heat and to present a surface which can be readily detached from the rubber after vulcanization. Certain mold forms at the edges of the box have presented difficulties of construction particularly where the parts are subjected to the tremendous strains to which these parts are subjected in forcing the plastic material to the different parts of the box under the pressure of the press. With the present invention, the cores are of sufficient strength to retain their shape and adjustable so as to maintain the walls of the box, the sections being provided with thimbles giving a material more readily detached from the rubber than materials having the desired strength for the body of the core. The present invention also obviates the difficulty as to the pattern shapes. Other features and details of the invention will appear from the specification and claims.

The invention is illustrated in the accompanying drawings as follows:—

Fig. 1 shows a side elevation of a portion of a press with a core in place, partly in section.

Fig. 2 a view of a portion of a press at right angles from that shown in Fig. 1.

Fig. 3 a section of the core on the line 3—3 in Fig. 1.

Fig. 4 a section on the line 4—4 in Fig. 1.

1 marks the head of the press, 2 the rods extending from the press to the usual base (not shown), 3 a steam-heated plate secured to the head by screws 3^a, and 4 the usual dowel pins for assuring the registering of the ram (not shown) with the head.

The core is supported on a plate 5. Rods 6 are screwed into the sides of the plate 5. These have the heads or up-turned ears 7 opposing the faces of the plate 3 and screws 8 are screwed through the ears against the plate

3 thus securely clamping the plate 5 on the plate 3 and at the same time affording a means of adjustment by means of the screws 8 for the plate 5.

The core base 9 extends from the plate 5. This base has slots 10 forming the core projections 11. Thimbles 12 extend over the projections 11 and are secured thereon by screws 13 extending through the bottom of the thimble into the bottom of the projection.

The base 9 with its projections 11 are preferably made of steel and the thimbles are preferably of aluminum or some similar material readily detaching itself from the rubber. The interposing of the thimbles between the projections 11 make it possible to make the slots 10 wide enough so that they can be readily machined, the space between the thimbles representing the thickness of the partitions in the battery box and being quite narrow.

It is sometimes desirable to form some pattern around the top edge of the box and it is difficult to form this pattern on the face plate of the mold. With the present invention this is accomplished by inserting a pattern plate 14 between the bottoms of the thimbles and the base plate, the plate 14 being clamped by the thimbles on the plate. In the present instance the pattern plate has a rib 80 surrounding each core projection, thus forming a groove in the top face of the battery box.

The present construction forms a very rigid construction which readily sustains the strains to which the core is subjected in putting the material under pressure as it is initially formed in the box. It permits of the use of integral projections of steel with a facing of material which will readily detach from the rubber at the completion of vulcanization and it also permits of the ready adjustment of the core so as to maintain an equal thickness of walls of the box.

What I claim as new is:—

1. In a battery box mold, the combination of a core base plate; core projections formed on the base plate; thimbles arranged over the projections; and a pattern plate clamped between the thimbles and the base plate.

2. In a battery box mold, the combination of a core base plate; core projections formed on the base plate; thimbles arranged over the projections; and a pattern plate clamped between the thimbles and the base plate, said pattern plate having pattern ribs surrounding each projection.

In testimony whereof I have hereunto set my hand.
